(57) **CLAIM**

The ornamental design for a washing machine with clothes dryer, as shown and described.

DESCRIPTION

FIG. 1 is a front perspective view of a washing machine with clothes dryer, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is an enlarged detail view of the portion 8 in FIG. 1;

FIG. 9 is an enlarged detail view of the portion 9 in FIG. 2;

FIG. 10 is an enlarged detail view of the portion 10 in FIG.

2;

FIG. 11 is an enlarged detail view of the portion 11 in FIG.

4;

FIG. 12 is an enlarged detail view of the portion 12 in FIG.

5;

FIG. 13 is an enlarged detail view of the portion 13 in FIG.

6; and,

FIG. 14 is an enlarged detail view of the portion 14 in FIG.

7.

The even-dash broken lines illustrating portions of the

washing machine with clothes dryer form no part of the

claimed design. The dot-dash broken lines indicates cutoff

(Continued)

boundaries for the enlarged detailed portion of the washing machine with clothes dryer form no part of the claimed design.

1 Claim, 14 Drawing Sheets
